[57] CLAIM

The ornamental design for a prime mover vehicle for
pulling or lifting a load, as shown and described.

DESCRIPTION

FIG. 1 is a front perspective view of a prime mover
vehicle for pulling or lifting a load embodying my new
design;

FIG. 2 is a side elevational view thereof, the side oppo-
site being substantially a mirror image of the side
shown;

FIG. 3 is a front elevational view thereof;

FIG. 4 is a top plan view thereof; and

FIG. 5 is a rear elevational view thereof.

Fig. 1.

Fig. 2.

Fig. 3.

Fig. 4.

Fig. 5.
